UNITED STATES PATENT OFFICE.

CARROLL D. YOUNG, OF SACRAMENTO, CALIFORNIA.

DESIGN FOR A FRONT SIGNAL CASING.

Application filed March 9, 1926. Serial No. 16,848. Term of patent 7 years.

To all whom it may concern:

Be it known that I, CARROLL D. YOUNG, a citizen of the United States, residing at Sacramento, in the county of Sacramento and State of California, have invented a new, original, and ornamental Design for a Front Signal Casing, of which the following is a specification, reference being had to the

accompanying drawing, forming part thereof, and in which the figure on the drawing is a perspective view of a front signal casing showing my new design.

I claim:

The ornamental design for a front signal casing, as shown.

CARROLL D. YOUNG.
